UNITED STATES PATENT OFFICE.

JOHN H. LEWIS, OF CICERO, ILLINOIS.

WALL CONSTRUCTION.

1,414,425.

Specification of Letters Patent. Patented May 2, 1922.

Application filed January 21, 1921. Serial No. 438,947.

To all whom it may concern:

Be it known that I, JOHN H. LEWIS, a citizen of the United States, and a resident of Cicero, in the county of Cook and 5 State of Illinois, have invented a new and useful Improvement in Wall Constructions.

My invention relates to improvements in wall constructions, and it consists in the combinations, constructions, and arrangements herein described and claimed.

An object of my invention is to provide a wall construction that is made up of a suitable supporting frame and slabs of a hardened plastic material provided with 15 means for securing the slabs to the frame in determined positions.

A further object of my invention is to provide a wall construction of the type described in which the slabs may be readily 20 secured to the supporting frame without any necessity for providing any auxiliary fastening means, wherefore a strong and durable wall can be formed at a relatively low cost.

25 A further object of my invention is to provide in a wall construction of the type described a building slab formed of a hardened plastic material and having a combined reenforcing and securing member partly 30 embedded therein.

Other objects and advantages will appear in the following specification, and the novel features of the invention will be particularly pointed out in the appended claims.

35 My invention is illustrated in the accompanying drawings, forming part of this application, in which—

Fig. 1 is a vertical section through a wall formed in accordance with my invention;

Fig. 2 is an enlarged horizontal section through the wall shown in Fig. 1;

Fig. 3 is a perspective view of a building slab embodied in a modified form of the 45 device,

In carrying out my invention, I provide a suitable supporting frame mounted on a foundation wall 1 and preferably consisting of a horizontal base member 2 50 mounted by vertical studs 3 maintained in spaced apart relation by spaced apart horizontal strips 4 which are secured thereto in any suitable manner as by means of nails. The base member 2 is likewise se-

cured to the foundation wall 1, which is 55 preferably of concrete or the like, by ordinary means such as an anchor bolt 5.

The construction described so far is ordinary and forms no part of my invention, except in so far as it cooperates with the 60 parts to be hereinafter described.

Referring now particularly to Figures 1 and 2 of the drawings, it will be noted that I provide a plurality of slabs denoted generally at 6. These slabs are formed of a 65 hardened plastic material, such as concrete and may be any size and shape desired, these characteristics being determined by the design of the wall construction decided upon. The slabs 6 are preferably formed 70 with the usual reenforcement consisting of wire netting 7 embedded therein intermediate the side walls thereof and extending substantially the length and width of the slabs. Interwoven with the reenforcement 75 7 in each slab is a combined reenforcing and securing member 8 preferably composed of one or more strands of galvanized wire having a diameter determined by the size of the particular slab in which embedded. The combined reenforcing and securing member 8 is arranged to extend the entire length of the slab 6 intermediate the side walls thereof and approximately 80 midway between its upper and lower walls 85 and is formed to provide spaced apart loops 9 that project through a side wall of the slab, as clearly shown in the drawings.

The slabs 6 are arranged relative each other in accordance with any predetermined 90 plan, and may be disposed in substantially edge-wise superposed relation with spaces 10 provided between the adjacent walls thereof for receiving a binding material, such as mortar 10', although the use of any binder 95 is not necessary in forming a wall construction embodying my invention. The slabs are secured in arranged position by means of tie members 11, which are passed through the loops 9 and then secured to adjacent 100 members of the supporting frame, such as the studs 3. Each of the tie members 11 in the form of the device illustrated, consists of a single piece of wire passed through the loop 9, then around one of the studs 3 and 105 having its ends twisted together to insure a taut connection between the stud and the slab.

From the foregoing description of the various parts of the device, the operation thereof may be readily understood. The slabs 6 may be placed in adjusted positions and secured therein in the manner described quickly and easily without any necessity for boring the slabs to receive anchoring members or the like, as in the case in forming walls by using concrete slabs of an ordinary construction. Likewise the slabs 6 may be removed if it is desired to wreck the wall and their removal may be accomplished without injury to the same. Consequently the same slabs may be used repeatedly in constructing different walls. The inner surface of the wall so constructed may be lined, if desired, in accordance with the ordinary practice by employing any suitable material, such as the lath and plaster shown more or less diagrammatically at 12. Since the wall embodying my invention can be constructed with the cost of labor and material reduced to a minimum, it is obvious that I provide a wall construction that is strong and durable and at the same time relatively inexpensive.

In Fig. 3 of the drawings, I show a modified form of a slab fashioned in accordance with my invention. The slab 20 is formed of a hardened plastic material and differs from the slab 6 hereinbefore described principally in size, and may be appropriately designated as a block. It will be noted that the slab or block 20 is provided with the usual reenforcement 7 and with the combined reenforcing and securing member 8. The block 20 is shown as being provided with only one of the loops 9 but obviously as many loops 9 would be provided in service as are necessary to secure the block in adjusted position.

The blocks 20 are secured to the supporting frame in predetermined relative positions in the manner hereinbefore described and consequently a further description of the

operation of the modified form of the device is unnecessary.

Obviously, the combined reenforcing and securing members 8 may be vertically disposed in the slabs and may be formed of any suitable material without departing from the spirit and scope of my invention as disclosed in the foregoing specification and outlined more particularly in the appended claims.

I claim:

1. In a wall construction, a slab made of a hardened plastic material, said slab having a reenforcing and binding screen disposed between the faces thereof, and a reenforcing wire disposed adjacent to and on one side of said screen, said wire terminating at the sides of said slab and being provided with a laterally extending loop midway between its ends, said loop being adapted to project outwardly from said slab.

2. In a wall construction, a slab made of a hardened plastic material, said slab having a reenforcing and binding screen disposed between the faces thereof, and a reenforcing wire disposed adjacent to and on one side of said screen, said wire terminating at the sides of said slab and being provided with a laterally extending loop midway between its ends, said loop being adapted to project outwardly from said slab and projecting through said screen.

3. In a wall construction, a slab made of a hardened plastic material, said slab having a reenforcing and binding screen disposed between the faces thereof, and a reenforcing wire disposed on one side of said screen and being projected through said screen and exteriorly of said block to form a loop, whereby the loop is disposed on one side of said screen while said wire is disposed on the opposite side.

JOHN H. LEWIS.
